UNITED STATES PATENT OFFICE.

SAMUEL MITCHELL, OF NEWARK, NEW JERSEY, ASSIGNOR TO L. FRITZSCHE & CO., OF NEWARK, NEW JERSEY, A FIRM.

DESIGN FOR A BRACELET.

No. 39,037.

Specification for Design.

Patented Jan. 28, 1908.

Application filed August 15, 1907. Serial No. 388,737. Term of patent 7 years.

To all whom it may concern:

Be it known that I, SAMUEL MITCHELL, a citizen of the United States, residing at Newark, in the county of Essex and State of New Jersey, have invented a new, original, and ornamental Design for Bracelets, of which the following is a specification, reference being had to the accompanying drawing, forming part thereof.

The figure of said drawing is a perspective view showing more particularly my new, original, ornamental design.

I claim:

The ornamental design for a bracelet, as shown.

SAMUEL MITCHELL.
